United States Patent Office

Des. 208,903
Patented Oct. 17, 1967

208,903

CLEANING DEVICE FOR AUTOMOBILE ENGINES AND COMPONENTS THEREOF OR THE LIKE

Emil Zadron and Alton S. Kenmonth, Los Angeles, Calif.,
assignors to Jet-Clean Co., Los Angeles, Calif., a
partnership

Filed Sept. 30, 1966, Ser. No. 4,099

Term of patent 14 years

(Cl. D9—2)

FIG. 1.

FIG. 2.

FIG. 1 is a front perspective view of a cleaning device for automobile engines and components thereof showing our new design; and

FIG. 2 is a rear perspective view thereof.

We claim:

The ornamental design for a cleaning device for automobile engines and components thereof or the like, substantially as shown.
